(57) **CLAIM**

The ornamental design for a chain-guide for cycle gear, as shown and described.

DESCRIPTION

FIG. 1 is a front left perspective view of a chain-guide for cycle gear.

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a front right perspective view thereof.

The broken line illustrations in the drawings depict portions of the chain-guide for cycle gear that form no part of the claimed design.

1 Claim, 6 Drawing Sheets
